(57) **CLAIM**

The ornamental design for a tyre, as shown and described.

DESCRIPTION

FIG. 1 is a front elevation view of a tyre in accordance with our new design;

FIG. 2 is a right side view thereof;

FIG. 3 is a perspective view thereof;

FIG. 4 is an enlarged view of a portion of FIG. 1;

FIG. 5 is an enlarged view of a portion of FIG. 2; and,

FIG. 6 is an enlarged view of a portion of FIG. 3.

The part of the drawings shown with a reduced tonal value, along with the broken-line perimeter, illustrates portions the tyre that form no part of the claimed design.

The dotted lines in FIGS. 1-3 show the boundary of the enlarged portions present in FIGS. 4-6 and form no part of the claimed design.

1 Claim, 6 Drawing Sheets(56)
